UNITED STATES PATENT OFFICE

2,547,203

PIN SETTING MACHINE

Charles E. Goff, Sherrill, N. Y.

Application November 27, 1946, Serial No. 712,703

3 Claims. (Cl. 273—42)

1

This invention comprises novel and useful improvements in a pin setting machine and more specifically has reference to an apparatus for automatically depositing a set of pins upon a bowling alley and spotting them in the correct position for play; which apparatus includes a pin supporting structure movable towards and away from a bowling alley and which will automatically release the pins carried thereby when at a position of nearest approach to the bowling alley.

The principal object of this invention is to deposit and accurately position an entire set of bowling pins simultaneously upon a bowling alley automatically by apparatus that readily lends itself to remote control.

Another important object of this invention, in conformity with the preceding object, is to provide a mechanism wherein the entire set of pins may be simultaneously engaged and released and wherein the release of the pins is positively synchronized with the movements of the pin supporting structure towards and away from the alley.

These, together with various ancillary objects of the invention which will later become apparent as the following description proceeds, are realized by this invention, one embodiment of which has been illustrated by way of example only in the accompanying drawings, wherein like numerals indicate similar parts throughout the various views and wherein:

Figure 1 is a top plan view of the invention shown in the position for placing a set of pins upon a bowling alley;

Figure 2 is a side elevational view of the device showing a set of pins placed upon the bowling alley and illustrating the operating mechanism in a position wherein the pin clutch means has just been released;

Figure 3 is a view similar to Figure 2 but showing the device in its retracted position and with a second set of pins engaged in the device ready to be placed upon the alley in its proper turn;

Figure 4 is a lower plan view of the device illustrating the manner of attaching the pin clutch jaws thereto;

Figure 5 is a front elevational view of the device;

Figure 6 is a vertical sectional detailed view taken substantially upon the section line 6—6 of Figure 5;

Figure 7 is a fragmentary detail view in section through one of the pin clutch members illustrating the clutch jaws gripping a pin;

Figure 8 is a view similar to Figure 7 but

2

illustrating the clutch jaws in their released position; and,

Figure 9 is a wiring diagram of the electrical circuit employed in operating the invention.

5 In the accompanying drawings, wherein a preferred embodiment of the invention has been illustrated, 10 designates a portion of a bowling alley having a pin pit 12 and a backstop wall 14. The alley and pin pit are bounded at their sides 10 by the customary side walls 16 and a compartment 18 is disposed in back of the backstop wall 14 for housing and appropriately mounting an operating mechanism for the pin setting device.

As shown best in Figures 2 and 3, the backstop 15 wall 14 is provided with suitable apertures 20 through which extend a pair of levers or operating arms 22 pivotally mounted in a suitable manner at the rear of the wall 14 as indicated at 24. As shown best in Figures 1 and 4, the levers or 20 arms 22 have right angularly disposed extremities 26 at their outer ends which are adapted to engage and are attached in any suitable manner to a rack which is preferably of triangular shape and is designated at 28.

25 The rack is provided with a plurality of apertures 30 in suitably spaced positions for loosely receiving and positioning a conventional set of bowling pins as at 32. As will be understood, the rack is so mounted and the apertures 30 are so spaced that when the rack is lowered in a manner 30 to be set forth hereinafter, the set of pins received in the apertures 30 will be placed and properly spotted upon a bowling alley in position for play.

As shown best in Figures 2, 5 and 6, the rack 35 28 is provided with a plurality of downwardly extending stop or abutment means indicated at 34, which are cushioned at their lower ends and are adapted to support the rack at a predetermined and desired height above a bowling alley without injury to the surface of the latter.

40 Attention is now directed more particularly to Figures 1, 4, 5 and 6 wherein there is disclosed an automatically operated pin engaging and releasing means. Pivotally mounted upon the rack 28 is a frame support consisting of a pair of side arms 38, pivoted as at 40 to the sides of the triangular frame adjacent the rear end thereof. The frame proper consists of a pair of angle iron members 42 disposed upon the outside of the sides of the triangular rack 28 and extending parallel thereto, and connected at their ends and intermediate their ends by transversely extending angle iron bars or cross members 44. This last mentioned construction is shown best by the 45 lower plan view of Figure 4.

Intermediate the ends of the members 38, are

depending bolting means 46 extending through the lateral flanges of the angle iron frame members 42 intermediate their extremities, and vertically adjustably engaging the same as by means of screw threaded nuts 48. It will thus be seen that as the levers 38 are raised or lowered about the pivot points 40, by a means to be later set forth, the connection 46 and 48 causes the raising and lowering of the frame side members 42 and the transverse bars 44 extending therebetween on vertical depending guide bars or hangers 47 carried by the rack 28.

As shown best in Figures 5 and 6, a pair of brackets 50 is mounted underneath the rack 28 immediately to the front and rear of each of the apertures 30. These brackets may be secured in any suitable manner as by welding, riveting, bolts or the like to the undersurface of the rack 28. Pivoted upon and depending from each pair of brackets 50, is a set of clutch members or clutch jaws 52, there being two such jaws disposed at each aperture 30, said jaws being pivoted upon a common fulcrum 56 in each of the brackets 50. As shown more clearly in Figure 8, each of the clutch jaws 52 constituting a set is pivoted upon a common pin 56 secured in the brackets 50, and these jaws are provided with semi-cylindrical gripping surfaces 58 which are appropriately contoured to firmly engage the bulbous surface of a bowling pin 32 immediately below its portion of enlarged diameter. The clutch jaws 52 are positioned in proper relation to the sides of the bowling pin by means of depending arms 60 which support the jaws from the pivoting pin 56. It will thus be seen that when the jaws are closed as in the position shown in Figures 5 and 7, a bowling pin will be securely retained therein, while when the jaws are opened as shown in Figure 8, the rack 28 and depending frame may be lifted from the pins without disturbing the position of the latter upon the bowling alley.

As is well known in the game of bowling, the ten pins comprising said game are disposed in triangular formation in four rows, having four pins in the back row, three pins in the next row, two pins in the row next to the front, and one pin in the front row. This arrangement is shown in side elevational view in Figure 6, and as will be seen, the transverse bars 44 of the frame are disposed transversely between the four rows of pins. As shown best in Figures 4 and 6, each of the clutch jaws 52 is provided with a forwardly or rearwardly extending shaft 62 having a roller 64 at the end thereof, said roller being positioned to engage the upper surface of one of the angle iron transverse bars 44. As will be readily apparent from Figure 6, each of the shafts 62 extends forwardly of its clutch jaw, except the shafts upon the clutch jaws of the single clutch member of the first row, which extend rearwardly whereby the three sets of clutch jaws of the first and second rows of clutch members are engaged with the same transversely interposed member 44. The shafts 62 are so located relative to the center of gravity of the clutch jaws 52, that when the side members 42 and the transverse members 44 are lifted in a manner to be set forth hereinafter, the rollers 64 and shafts 62 are elevated to thereby cause an opening movement of the clutch jaws as shown in Figure 8. During this movement, it will be seen that the rollers 64, move apart upon the transverse bar 44 as shown in Figure 8.

Attention is next directed to Figures 2 and 3 for an understanding of the actuating means for

the rack and the frame. Upon a suitable support 66 in the compartment 18 to the rear of the backstop 14, is mounted an electric motor 68 which by suitable gearing indicated at 70 drives at an appropriate speed a crank shaft 72 having a crank arm 74 thereon. This arm rotates in a clockwise direction as indicated by the arrows in Figures 2 and 3. It should be here noted that a counter-clockwise rotation would not be capable of imparting the desired motion to this device.

As shown best in Figure 1, the crank shaft 72 will preferably be provided with a crank arm 74 at each extremity thereof and these crank arms terminate in crank pins 76. These crank pins 76 are connected to angularly offset crank pins 78 by a crank throw 80, the pins 76 and 78 being disposed at different radial distances from the axis of the crank shaft 72 and also upon different radii thereof.

20 A support means having a pair of longitudinally disposed arms 82, vertical pillars or standards 84 and a transverse bar 86 is secured in any suitable manner to the backstop wall 14 and to the side walls 16 of the bowling alley. 25 Four pulleys or sheaves 88 are journaled upon the bar 86, and four cables are entrained over these pulleys and fastened to the four crank pins 76 and 78. To the inner pins 76 a pair of cables 90 are connected and entrained over a pair of the pulleys 88 and are connected to the forward ends of the actuating levers 38 upon which is supported the frame mentioned hereinbefore. To the outer crank pins 78 a second pair of cables 92 are connected and are entrained over further pulleys 35 88 and connected at convenient points to the sides of the rack member 28.

From the foregoing, it is believed that the manner of operating the mechanism will be now readily understood. With the rack and frame in the 40 raised position, as is shown in Figure 3, a set of pins may be inserted in the clutch jaws 52 through the apertures 30 and will be retained therein by virtue of the clutch members or jaws having centers of mass that cause the same to be urged to a pin engaging position by gravity to hold the pins for subsequent placement upon the alley. In order to permit this operation, the 45 crank pins and cables are in the position shown in Figure 3, wherein the crank pins 78 and the cables 92 are in their extreme rearward position relative to the crank shaft 72, and the rack is elevated to its greatest extent about its pivot point 24. At the same time, the crank pins 76 and attached cables 90, are likewise in their rear- 50 most position, and the lengths of the cables 92 and 90 are so adjusted that the clutch jaws 52 are now closed by gravity gripping the pins 32 therebetween. When the bowling has been temporarily completed upon the alley, and it is desired to re-set the pins thereon, the electric motor 68 is energized by a means to be subsequently 55 set forth causing the rotation in a clockwise direction of the arms 74. As the crank pins 76 and 78 rotate, the cables 90 and 92 are allowed 60 to move forward, thereby lowering the rack and frame upon the rigid supporting arms or levers 22. This operation continues until the rack is in its fully lowered position shown in Figures 5 and 6, with the pins placed upon the alley on 65 their proper spots, and with the abutment members 34 upon the surface of the alley thereby limiting and stopping further downward movement of the rack. As the crank arms 74 continue to rotate into the position shown in Figure 2, the 70 crank pins 76 tighten the cables 90, thereby lift- 75

ing the frame support levers 38 about their fulcrums 40, and thereby elevating the frame side members 42 and transverse bars 44, into the position shown in Figure 2. As the frame members are elevated, the rollers 64 are actuated to open the clutch jaws whereby the pins are freed from their gripping means. As the crank arms 74 continue to rotate, both cables 90 and 92 are now drawn in, and the rack and frame move up as a unit into the position shown in Figure 3.

Particular attention is directed to the arrangement of the crank pins 76 and 78 and their connecting crank arms or crank throws 80 as shown in Figures 1, 2 and 3, since it is the angular positions and arrangements of the parts which cause the properly timed sequence of movement of the cables 90 and 92 to perform the above mentioned step in the operation of the device.

In order to control the operation of the motor and the automatic functioning of the pin setter device, a suitable electric control means is provided as indicated diagrammatically in Figure 9. The actual construction of the motor control means forms no part of this invention, and any suitable construction thereof may be employed, that shown in Figure 9 being one satisfactory embodiment of the same. Current from any suitable source is supplied from a pair of leads indicated generally at 94 under the control of a pair of manually operable switches 96 and 98 arranged in parallel with each other for selective operation of the motor 68. Preferably, one switch such as 96 may be disposed adjacent the bowling foul line, whereby it may be operated by the bowler himself, while the other switch 98 may be located in the pin pit where it may be operated by a pin boy or other attendant. Each switch 96 and 98 is held in its normal open position by a spring means 100, but when closed is maintained in closed position by a solenoid 102. A solenoid switch 104 is connected by a link 106 with each of the manual switches 96 and 98 for simultaneous actuation thereof.

The arrangement is such that the manual switches 96 and 98 and their inter-linked solenoid switches 104 are normally held open by the springs 100. When however either switch 96 or 98 is closed, the solenoid switch 104 is likewise closed and current may flow through the positive lead 108 into both the solenoid 102 and the selected switch 96 or 98 and then by lead 110 to the motor 68 for actuating the same. The solenoid 102 functions to maintain both switches 104 and 96 or 98 in their closed position until a release switch indicated generally at 112 breaks the flow of current through leads 108, 110 and the motor 68. The release switch 112 is synchronized with the operation of the motor 68, as by a cam operated thereby, whereby after a predetermined operation of the motor 68 such as is necessary to make one revolution of the crank shaft 72, the circuit is broken whereupon the spring 100 opens the manually operable switch. By this means, the motor is manually set in operation, and after performing one cycle of operation of the pin set-

ting machine as set forth hereinbefore, the circuit is automatically broken, and the parts stopped in the position which they had initially assumed.

It is to be distinctly understood that the foregoing description and the drawings are to be regarded as illustrative of the principles of the invention only, and are not to be taken as limiting the scope of protection which it is desired to obtain. Accordingly, all suitable modifications and equivalents may be resorted to within the scope of the appended claims.

What is claimed as new is as follows:

1. In a pin setter, a rack having apertures for receiving a plurality of bowling pins in predetermined relation, a frame, means carried by and depending from the rack for slidably guiding vertical movement of the frame relative to the rack, a release element pivoted to said rack and connected to said frame for selectively raising and lowering said frame relative to said rack, pairs of jaws pivoted to said rack with the jaws of each pair normally urged towards each other to grip a bowling pin therebetween, and release means carried by said jaws engaging said frame and responsive to upward movement of the frame relative to the rack to release said jaws, and operating means for said rack and said release element comprising a rotatable rigid member, means for effecting rotation of said member, first and second holders carried by said rotatable member, said second holder being further from the axis of rotation than said first holder, one of said holders angularly trailing the other, a first flexible connector connecting said rack to said second holder, and a second flexible connector connecting said release element to the first mentioned holder for synchronized actuation of said rack and releasing element upon rotation of said rotatable member.

2. The combination of claim 1, wherein said jaws pivotally depend from said rack, said jaws having enlarged offset lower end portions urging said jaws towards a pin engaging position by gravity.

3. The combination of claim 2, wherein common pivot pins are provided to pivot the opposing jaws of each pair of jaws.

CHARLES E. GOFF.
